VENDING MACHINE

Roy H. Summerfield, Vancouver, British
Columbia, Canada

Application September 24, 1947, Serial No. 775,813

1 Claim. (Cl. 312—56)

1

My invention relates to improvements in vending machines which are particularly adapted for vending newspapers and the like.

The objects of the invention are to provide a mechanism whereby a stack of newspapers to be dispensed are moved to present each one progressively into a given position; to provide means for lifting the foremost paper from the stack and for delivering the lifted paper into a receiving rack in response to the rocking movement of a shaft.

The invention contemplates an inclined bed plate for receiving a stack of newspapers, and means for supporting the newspapers at a suitable angle for dispensing, and means for progressively removing a newspaper from the front of the stack.

Referring to the drawings:

Figure 1 is a front elevational view of the invention showing the cover in open position.

Figure 2 is a plan view showing the dispensing mechanism.

Figure 3 is a transverse sectional view taken on the line 3—3 of Figure 1.

Figure 4 is an enlarged sectional view of the article lifting mechanism.

In the drawings like characters of reference indicate corresponding parts in each figure.

The numeral 1 indicates a cabinet having a base 2, side walls 3, front wall 4 and a hinged top cover 5. The top cover 5 is provided with a window 7 through which a purchaser may assure himself as to papers being available and read a portion of the title sheet of the paper therein displayed.

Intermediate the height of the cabinet 1 is an inclined bed plate 9 which extends downwardly towards the front wall 4 and connects with an apron 10 which is steeply inclined downwardly. The apron 10 terminates in a channel 12 which is adapted to arrest the downward movement of a paper dispensed from the machine and is provided with a gap 14 intermediate the length of the channel to afford access to the lower edge of a paper to lift it out of said channel. The upper portion of the front wall 4 forms a panel 16 on which a portion of a coin lock mechanism 17 of any suitable type is mounted. A horizontal rectangular housing 20 is mounted between the side walls 3 and is provided with a removable top closure 21 for excluding the mechanism therein from view through the window 7.

Mounted within the housing 20 is a horizontal shaft 23 which is rocked through gears 24 and 25 from a stub shaft 26, which stub shaft is fitted

2

with a hand crank 27 projecting from the right side wall 3 of the casing 1 and is appropriately freed for operation by the coin lock mechanism 17 in response to the insertion of a coin. The shaft 23 is fitted with two or more cranks 29 having crank pins 30 upon which fingers 31 are rockingly mounted. Each of the fingers 31 is provided with a pointed end 33 which is normally retracted within the housing and is adapted to project through a slot 34 formed in the front wall 36 of the housing 20. The inner end of the finger 31 extends beyond its crank pin 30 and is apertured as at 38 to engage a tension spring 39 which is anchored to a pin 40 carried by the crank 29 adjacent the shaft 23, which spring tends to urge the point 33 of the finger away from the shaft 23 and towards the papers disposed upon the bed plate 9.

Adjustably mounted on the inner face of the wall 36 of the housing 20 is a gate 43, having slots 44 which register horizontally with the slots 34 of the wall, the base of these slots, indicated by the numeral 45, act as stops to limit the downward swing of the point 33 of the fingers 31 about their crank pins 30. The gates are held in adjusted position by thumb nuts 47 or by other appropriate means. The fingers 31 are retracted to the position shown in Figures 3 and 4 by any appropriate spring means, the means here shown being a tension spring 49 anchored at one end to the base of the housing 20 as at 50 and at the upper end to an arm 51 extending radially from the stub shaft 26.

A plate or follower 55 having rollers 56 at its lower rear edge is mounted upon the bed plate 9 for movement therealong. The plate 55 extends substantially from side to side of the interior of the casing 1 and is supported in inclined position by a pair of legs 57 which are hingedly connected to said plate adjacent its upper end as at 58 and are hingedly connected to the bed plate 9 adjacent their lower ends as at 59. At the front edge of the bed plate 9 a plurality of thin stops 61 are provided, which engage the lower edge of each newspaper as it slides along the bed plate in advance of the follower 55. The follower 55 assumes an inclined position when in its rear-most position, substantially as shown in Figure 3, which is such as to prevent the newspapers supported against it from curling over towards the front wall 4 and as each paper is removed the angle between said follower and the legs 57 will become less acute.

In operation when a coin has been inserted 55 into the coin mechanism 17 the hand crank 27

is rocked, imparting a clockwise rocking motion to the cranks 29, as seen in Figure 4, causing the points 33 of the fingers 31 to swing outwardly and upwardly through the slots 34 in the wall of the housing 20 and along the path shown in dotted line in Figure 4, to engage the foremost paper on the bed plate 9. As soon as said paper is raised above the stops 61, the forward movement of the follower 55, stimulated by the tendency of the triangular structure formed by the follower 55 and the legs 57 to collapse or spread causes the stack of newspapers to move forward and bring the paper immediately behind the one lifted by the fingers, into contact with the stops 61, so that as the fingers 31 are retracted, incidental to the reverse rocking movement of the shaft 23, the foremost paper is lowered between the stops 61 and the front wall 36 of the housing 20 and as soon as the points 33 are withdrawn from contact with said paper, it will drop between the walls 4 and 10 into the channel 12 from whence it can be removed by the purchaser.

What I claim as my invention is:

A vending machine comprising a casing having an article delivery opening in one side, a bed plate mounted within the casing having a free edge above the delivery opening, a follower adapted for automatic movement across the bed plate towards its free edge to move a stack of articles

5 supported on their edges in face to face relation upon the bed plate, said movement being towards said free edge, a stop projecting above the free edge of said bed plate to restrain the movement of the follower, a plurality of substantially horizontally disposed fingers rockingly mounted adjacent the free edge, said fingers being pointed at their free ends, said fingers being rockingly mounted adjacent their rear ends upon a crank and being slidably supported adjacent their pointed ends upon a horizontal member, manually operable means for rocking the cranks in one direction to move said points into engagement with an adjacent article and lift it above the stops, and means for retracting said points to permit said lifted article to fall towards the delivery opening.

10 15 ROY H. SUMMERFIELD.
